UNITED STATES PATENT OFFICE

138,170

DESIGN FOR A PUMP

Joseph C. Woodford, Spring Lake, Mich., assignor
to John Wood Manufacturing Company, Inc.,
Philadelphia, Pa., a corporation of Delaware

Application April 15, 1944, Serial No. 113,265

Term of patent 14 years

(Cl. D65—1)

To all whom it may concern:

Be it known that I, Joseph C. Woodford, a citizen of the United States, residing at Spring Lake, in the county of Ottawa and State of Michigan, have invented a new, original, and ornamental Design for Pumps, of which the following is a specification, reference being had to the accompanying drawing, forming part thereof.

Fig. I of the drawing is a front elevation, and Fig. II is a side elevation of the pump, showing my new design.

The lower tube is shown broken away in the two views to indicate indeterminate length.

I claim:

The ornamental design for a pump, as shown.
JOSEPH C. WOODFORD.
